APPROACH PROTECTIVE SYSTEM

Glenn H. Browning, Winchester, Mass.

Application July 17, 1942, Serial No. 451,279

10 Claims. (Cl. 177—352)

1

The present invention relates to a protective system to guard against approach of persons or objects to a region or area to be protected, and more particularly to a system in which signal wires or signal networks may be strung around a given area and in which capacitance changes or other electrical changes may indicate and detect the approach of persons or objects to the signal wires or network.

The present invention has numerous advantages over other systems of the prior art particularly in providing a system which is little or not at all affected by climatic changes such as may occur during different times of the year or by accumulation of snow and ice or change of ground conditions or atmospheric moisture or other variable conditions bound to exist in the use of the invention out of doors. These results are accomplished by the apparatus itself, by reason of the design and layout of the signaling system or by these features in combination with compensating means and methods which maintain a constant differential relation between dual parts in the system itself.

A fundamental advantage of the present invention is a self-balancing feature which is brought about by employing two signal wire networks connected to the end apparatus. If the two signal wire networks are substantially equal, the end apparatus is preferably adjusted in the initial installation so that equal capacitance changes on both signal wire network allows the system to remain in balance. If it is not feasible to have the two signal wire networks of similar length, the end apparatus is preferably adjusted on the initial installation, so that if equal capacitance changes per unit length occur on both signal wire networks the system will remain in balance.

A further advantage is obtained in the present invention by the use of two similar systems oscillating at frequencies which vary but which under normal operating conditions when the alarm does not sound have a constant differential frequency comprising a beat note produced by the beating of different harmonics of the oscillators. The use of harmonics for the production of the beat note in the present system has a further advantage of permitting the oscillators to operate at considerably different frequencies and thereby preventing intercoupling or interconnection between two oscillators.

A still further advantage in the use of the harmonics of the oscillator is that the sensitivity of the system may be greatly increased be-

cause a small change in the fundamental frequency may be made to produce a considerably greater change in the harmonics which are used.

5 A further feature of the present system is that the beat note used is that obtained from different harmonics of the fundamentals preferably harmonics which are sufficiently close together as to produce an audio frequency note approximately within the range of 1000 cycles.

The signal wire system or signal network system may be used with other operating apparatus as for instance a balanced bridge circuit in which the variation of the capacitance in the signal wire system or network upsets the balance of the bridge but as a whole there is a marked advantage in the use of two separate oscillators especially where conditions vary from time to time.

Further advantages will be readily understood from a consideration of the specification set forth below when taken in connection with the drawings which are briefly described as follows:

Figure 1 is a block diagram of a simple form of electrical apparatus embodying the present invention. Figure 2 is a block diagram of a different form of electrical apparatus embodying the present invention. Figure 3 is a view illustrating one arrangement for protecting a region with the signal wires according to the practices of the present invention. Figure 4 is a circuit diagram corresponding to the block diagram of Figure 1. Figure 5 is the circuit diagram of the arrangement corresponding to the block diagram of Figure 2. Figure 6 shows the resonance characteristic curve of the selective audio amplifier which is used in the circuit diagram of Figure 5. Figures 7 and 8 illustrate signal wire installation outside and inside barbed wire fences respectively, and Figure 9 illustrates signal wire installation inside a chain link fence.

In Figure 3 of the present invention is shown an arrangement of the conducting wires guarding against the approach of anyone to it. It will be noted that these conducting wires form two separate wire networks 1 and 2, which are preferably counterparts of each other having, as closely as practical, the same lengths, geometrical arrangements and position with respect to the ground and other objects in their vicinity. If it is not possible to make the two signal wire networks or systems nearly the same because of permanent objects in the vicinity or if it is inconvenient to do so, the apparatus can be so adjusted that it may operate in accordance with the present invention either by making the oscillators proportionally adjustable in accordance

with the signal wire climatic changes or by use of a compensating system hereinafter described to compensate for unequal climatic and other slow changing conditions not brought about by the approach of foreign objects to within detection range of the signal wire networks.

As indicated in Figure 3 the signal wires are strung on insulator supports 3, 3, 3, etc., which are mounted on supporting beams 4, 4, etc., and on supporting poles 5, 5, 5, etc., either on the inside or on the outside of the barbed wire fence 6. The details of the construction and arrangement of the signal wires with respect to the fence are indicated more in detail in Figures 7, 8, and 9. It will of course be understood that the signal wires may be used alone without a fence, but in event that a metallic fence is used, the signal wire should be positioned at a certain distance away from the wire fence for best results in the manner described below.

Figure 3 also indicates the signal wire lead-in construction. Each of the signal wire networks 1 and 2 have independent lead-ins. The lead-in wire 7 for the network 1 is strung along a series of posts from one of the posts 5 to the housing 8 containing the apparatus. From the post 5 the lead-in wire is extended downward to join the signal wire network at the junction 9. Similarly the lead-in wire 10 extends from the junction 11 of the network 2 to a post 5 and then to the housing for the apparatus 8.

Figure 3 also illustrates the dead end construction of the signal wire network. The network 1, for instance may be terminated at a certain central supporting section A, at its insulators 3, 3, respectively on the outer side of the supports 4 and 5 from which the wires extend to a support 12 located somewhere between the top signal wire 13 and the bottom signal wire 14 forming a part of the signal network 1. These end wires 15 and 16 may be joined together or may be strung as one continuous wire. The signal network 2 is similarly terminated in the end section A with the top wire 17 of the network 2 supported by an insulator 3' on the inner side of the beam 4 and the signal wire 18 of the network 2 supported on the inner side of the post 5 by the insulator 3''. These wires are similarly joined together by the end wires 15' and 16' supported to the beam 12 by suitable insulators.

The simplified block diagram of Figure 1 shows at the left the terminals of the lead-in wires 7 and 10 of the signal wire networks 1 and 2. These are connected to the inputs of their respective oscillators 20 and 21, and then to ground as shown in Figures 1 and 2. The oscillators will be more fully described later, it being sufficient to note for the present that each of these oscillators is preferably tuned to considerably different frequencies differing for instance by approximately 25,000 cycles when each is tuned in the neighborhood of 100 k. c. Higher frequencies may be used for the fundamentals of these oscillators and the difference in frequency between the two oscillators may likewise be greater. By keeping the fundamental frequencies of the oscillators 20 and 21 sufficiently far apart, it is possible to avoid electrical coupling between the two oscillators as may occur with a common ground return and thereby prevent variations in the oscillator frequencies which occur between two coupled circuits. The mixer circuit 22 functions to detect a desired beat note corresponding to the difference between certain desired harmonics of the fundamental frequencies of the oscillators 20 and

21. This beat note may be chosen for instance as the beat note existing between the third harmonic of the oscillator 20 and the fourth harmonic of the oscillator 21, or other combinations of harmonics may be used as for instance the fifth and sixth harmonics or the second and third harmonics of the oscillators. As an illustration it has been found practical to use a beat frequency of the order of 500 to 1000 cycles developed by the third harmonic of one oscillator and the fourth harmonic of the other oscillator. The fundamental frequencies in this case may for instance be approximately 75 and 100 k. c. respectively for the oscillators 20 and 21. The output of the mixer circuit is impressed upon a selective audio amplifier 23 which may have a resonance characteristic curve of the shape shown in Figure 6. This selective audio amplifier may have a band pass at about 700 cycles with an attenuation of about 60 db. for 50 cycles either side of the normal operating frequency line.

If therefore the signal wire networks and their associated oscillators are so adjusted under normal operating conditions when no object is approaching the wires to produce a frequency impressed upon the selective audio amplifier corresponding to the normal operating frequency N, then the amplitude of the signal delivered by the selective audio amplifier to the rectifier 24 will be a constant maximum and remain so provided the difference frequency between the harmonics of the two oscillators remain the same. In certain places and under certain conditions where the signal wire systems are the same in most or all respects, this condition may remain true and changes occurring in weather and other climatic conditions will affect similarly the two signal wire systems so that the difference frequency may remain nearly the same. Under conditions where this is not the case, the arrangement indicated in Figure 2 which will be described later, is preferable.

In the system shown in Figure 1, the rectifier 24 is connected to a relay circuit and supplies sufficient power to the relay circuit to maintain it in an energized state while the normal beat frequency signal is being received and transmitted through the circuit. When the beat frequency varies because the difference frequency between the two oscillators 20 and 21 is changed, an amplitude less than the constant normal maximum amplitude is delivered to the relay circuit 25 which thereby releases and causes the operation of the alarm indicator 25. An advantage in this arrangement is that any failure of the power in the system will cause the alarm indicator to operate thereby assuring the watchman or guard that the system is always working while the beat signal note is present.

The circuit diagram, Figure 4, corresponding to the block diagram of Figure 1, shows a particular form of circuit which may be used. The terminal of the signal wire networks 1 and 2 are impressed upon similar oscillating circuits 50 and 51. These oscillator circuits comprise vacuum tubes 52 and 53 respectively, inductances 54 and 55 respectively, condensers 56 and 57 respectively, and grid condensers 28 and 29 respectively with grid resistors 30 and 31 respectively. The frequency of the oscillator 50 is determined by the inductance 54, the condenser 56 and the signal wire network 1 which provides chiefly a capacitance across the inductance 54 which is in parallel with the condenser 56. The inductance 54 may be variable and so also, if desired, the condenser

56. The frequency of the oscillator 51 is similarly determined by the signal network which is in parallel with the inductance 55 and the condenser 57 which may be tuned to provide initial frequency adjustment between the two oscillators. As has been stated above it is preferable to make the signal wire systems or networks similar as far as possible and equal in geometric dimensions so that the same changes in climatic conditions will affect both systems nearly equally. Since however the two oscillators are tuned to different fundamental frequencies, it is necessary, in order that equal variations in the capacitances to ground of the signal wire systems produce equal variation in the harmonics of the frequency of the oscillators 50 and 51, to provide the oscillator operating at the lower frequency with a greater inductance in its frequency determining circuit than the inductance in the frequency determining circuit of the oscillator operating at a higher frequency. This is shown in the mathematical relations worked out below. In the ordinary oscillating circuit the following relation exists

$$F = \frac{1}{2\pi\sqrt{LC}}$$

where F is the fundamental frequency of the circuit; L , the inductance and C , the capacitance. If the inductance in the two oscillator circuits were equal and if it is further assumed that the third harmonic of the oscillator 50 is used to beat against the 4th harmonic of the oscillator 51, then it may be shown that the length or capacitance of the two sections must be in the relation of 1 to 1.78 for a self balancing system. This would make one section of the signal wire system very much longer than the other section and as any inherent instabilities are proportional to the length of either section, the system would not protect the maximum area with maximum stability. By making the inductance of the two oscillators in the ratio of 1.78 to 1, the two sections can be made equal in length (substantially equal in capacitance). This situation is arrived at mathematically by the following procedure.

$$4f_2 - 3f_1 = K \quad (1)$$

Where f_1 and f_2 are the fundamental frequencies of the two oscillators, $4f_2$ is fourth harmonic of f_2 , $3f_1$ is third harmonic of f_1 . K is the audio frequency passed by the selective network. As K is very small compared to either f or f_2 ,

$$4f_2 \equiv 3f_1 \quad (2)$$

$$f_1 = \frac{1}{2\pi\sqrt{C_1 L_1}} \text{ and } f_2 = \frac{1}{2\pi\sqrt{C_2 L_2}} \quad (3)$$

It is proposed to make $C_1 = C_2 = C$. Therefore,

$$\frac{4}{3} = \sqrt{\frac{L_2}{L_1}} \text{ or } 1.78L_1 = L_2 \quad (4)$$

As described in connection with Figure 1 the outputs of the two oscillators are impressed upon the mixer circuit. In Figure 4 this mixer circuit is indicated as employing a multi element vacuum tube 33 which is resistance coupled to each of the oscillators 50 and 51 through the resistances 34 and 35. By using a multi element vacuum tube such as indicated in Figure 2, it is possible to reduce the coupling between the two oscillating circuits to a minimum so that they may always act independently of each other. The vacuum tube 33 may be of any suitable type, such for instance as the tube commonly designated as 6SA7.

The output of the mixer circuit is impressed upon the selective audio amplifier which comprises a degenerative vacuum tube circuit and amplifier and operates in the following way. All 5 audio frequencies are fed to the grid of the pentode tube 36 and are amplified. A net work is placed between the plate of this tube and the grid circuit to feed back in the reverse phase all frequencies except those frequencies close to the 10 particular frequency determined by the value of the capacitors and resistors in this feed back net work 37. Thus this tube passes no frequency except those frequencies close to the particular frequency determined by the feed back network. The signal coming from the selective audio amplifier is then amplified by the vacuum tube 38 and fed to a diode rectifier circuit, comprising the rectifier tube 39 with cathode 40 and anode 41 and the adjustable bias resistor 41'. The rectified signal is then filtered by a network comprising the capacitors 41 and 42 to ground and the resistor 43 connected to the cathode lead and then fed to the control grid 44 of the power tube 45 for controlling and operating the relay coil 46. The grid of the tube 45 which may be called the relay tube is so connected to the diode 39 that when a signal voltage is fed to the diode a positive voltage is impressed upon the relay tube which energizes the coil 46 holding in the 20 relay and preventing the operation of the alarm circuit. When there is a change in capacitance due to the approach of a person or object to one half of the signal wire system the signal voltage fed to the relay tube decreases and the relay armature 47 is allowed to make contact with the contact point 48 completing the circuit to the alarm plug 49 which may be energized from the A.C. source 60.

In order to compensate for any slow differential changes in capacitance which may occur, it is generally necessary to have some means for indicating the direction of compensation. Various methods having this feature may be used for producing the desired compensation. One 40 such method is employed in Figure 2. By the arrangement of Figure 2 it is possible to compensate for changes in climatic conditions as for instance accumulations of snow or rain on the signal wires or change in humidity temperature and other conditions affecting differentially the capacitance of the system. In this case a balanced 45 system is used, preferably one in which the two capacitance lines are of equal length in which case the greatest total area will be protected with the least unbalance effect. In this case oscillators 20' and 21' are combined in a mixer circuit 22 from which they are impressed upon a selective audio amplifier 23 which preferably has a characteristic curve of the type shown in Figure 6 in which the normal point of operation is indicated as about one half way up on one of the side slopes of the curve. Small changes in either direction of the frequency to points labelled high compensation and low compensation 50 merely operate to put in motion the compensating devices 61 and 62 for bringing the beat note frequency back to the line 'N' of normal operation. If sudden change in the beat frequency occurs of a magnitude greater than that corresponding to the points of high and low compensation either the high alarm relay circuit 63 or the low alarm relay circuit 64 will operate to actuate the alarm indicator 65. Both compensating devices 61 and 62 of both relay alarm circuits 63 and 64 are energized through the recti-

filters 66, 67, 68 and 69. The circuit of the block diagram of Figure 2 is indicated in Figure 5. The lead-in wires 7 and 10 in this case go to the oscillators 70 and 71. These oscillator circuits may be similar to that described in connection with Figure 4 with the exception that the oscillator 71 is provided with the compensating condenser 72 which is adjustable by means of the compensating motor 73 and 74 respectively to add or take out capacity in the oscillator circuit 71 and thereby change its operating frequency. This change in frequency of the oscillator 71 is adjusted to operate when the normal beat frequency (Figure 6) has varied on account of the climatic conditions acting on the signal network to produce sufficient variations in the harmonics of the fundamental frequencies of the oscillator 70 and 71 so that the oscillator beat frequency is near the point of high or low compensation correction as illustrated in Figure 6. The outputs of the oscillators 70 and 71 are impressed upon the mixer tube 83 which is connected to the selective audio amplifier circuit, tubes 84 and 75, which has an operating resonance characteristic curve of that shown in Figure 6. This circuit may be similar to that described in connection with Figure 4. The point of operation chosen for the rectifiers operated from its output however is on one of the slopes of the resonance curve preferably along its steep portion. Operated from the output of the amplifier tube 75 are the rectifier circuits 76 and 77 respectively. The rectifier circuit 76 comprises a diode rectifier 78 the output of which controls the grid 79 of a grid control gaseous conduction tube such as a "thyatron" tube 80 which in its output circuit has a relay coil 81 which operates the relay contact 82 to close the circuit to the compensating motor. The "thyatron" 80 associated with the rectifier tube 78 is so biased that when the signal fed from the audio amplifier is a little more than half way up the resonance curve (Figure 6), to the point of high compensation correction, the "thyatron" receives a sufficiently positive voltage on its grid with respect to its original negative bias so that it is fired. The output of the rectifier circuit 77 is fed to a "thyatron" tube 85 in the output of which is a second relay 86 controlling the operation of the electrical circuits across its armature switch 87. This diode rectifier 89 has a positive bias and its anode is connected through a suitable resistor and condenser network (similarly as in the rectifier circuit 76) to the grid 88 of the "thyatron" tube 85. The positive bias is required because the diode is so connected that the signal voltage makes the "thyatron" grid negative with respect to the original bias. When therefore the signal voltage is decreased the positive bias causes the "thyatron" tube 85 to fire operating the relay 86 to close the relay contact 87 and commence the operation of the compensating motor 73. These compensating motors 73 and 74 operate the condenser 72 to restore the beat frequency slowly to its normal value. The rate of restoration should be adjusted as low as consistent with the expected normal differential capacitance variations of the signal wire system at the particular location of the system.

The rectifier circuits 90 and 91 control the operation of the alarm indicator fed through the alarm outlet box 92. The diode 93 of the rectifier circuit 90 has its cathode connected through a suitable resistance capacitance network to the grid 95 of the "thyatron" tube 94. The output

of this "thyatron" tube controls the operation of a relay 96 operating a relay armature 97 for closing the contact to the alarm circuit. The bias associated with the diode rectifier 93 is so adjusted that when the signal voltage from the audio amplifier is near its peak, sufficient positive voltage with respect to the negative bias is developed on the grid of the "thyatron" 94 so that it fires, actuating the relay and operating the alarm.

In the rectifier circuit 91 a diode rectifier 98 similar to the rectifier tube 93 controls the grid 100 of a vacuum tube 99 through a resistance and capacity network. The diode rectifier tube 98 has a negative bias. The signal provides the grid with a positive voltage which is obtained by connecting the grid to the cathode of the rectifier so that for normal operation of the circuit sufficient plate current is passed through the vacuum tube 99 to keep the relay contacts 102 apart so that the alarm circuit will not operate. When the signal decreases, the positive voltage on the grid 100 diminishes and the relay which may be set for sensitive operation releases, closing the contacts to the alarm circuit.

Figures 7, 8, 9 show the construction of the signal wire systems or network.

It first may be mentioned that the signal wire should preferably be coated with a water shedding insulation, as for instance a suitable mica lacquer which will not readily allow water droplets to collect on the wire from rain.

The construction in Figure 7 is similar to that indicated in Figure 3 for the lead-in section and in this case it is assumed that the wire fence itself is supported by the posts 5 and that the signal wires are on the outside of the wire fence.

The construction indicated in Figure 8 shows the signal wire on supports 5' set up on an angle with the signal wire presumed to be on the inside of the barbed wire fence.

In Figure 9 the signal wire support 5''' is shown as inside the chain link fence 6'. The chief point to be noted in the constructions in Figures 7, 8, and 9 is that the signal wires are spaced apart at some distance from the wire fence. The spacing between parallels should be approximately three feet or more.

The signal wire systems may be set up to extend over a very considerable distance, sufficient to surround power plants, factories and other types of plants which it is desired to guard and warn of the approach of strangers or strange objects.

Signal networks or systems of 600 ft. or more are practical and where it is desired more than one system may be used as, for instance, one on one side of the plant and another on the other side of the plant. The system may also be used to guard small areas as for instance, entrances and doors and may also be used indoors in an equally efficient and useful manner as it is used out of doors. A large area may be covered by systems one adjacent to the other.

A short summary of the operation of the system with suitable chosen values is given below:

The capacitance of the two sections of the signal wire systems is carefully measured at approximately 100 kc. The two sections of the signal wire systems are then connected in turn to oscillators 70 and 71 for instance. Fixed condensers as required are connected across each oscillator. The value of these fixed condensers for a balanced system will be in the ratio of the capacitance of the alarm wires. Assume one

section of the signal wire system had a capacitance of 2000 micromicrofarads while the other "half" had a capacitance of 1800 micromicrofarads; the fixed condensers across the oscillator associated with the 2000 micromicrofarads might be 2000 micromicrofarads while in this case the fixed capacitance across the oscillator associated with the 1800 micromicrofarads would be 1800 micromicrofarads. This in general would result in a balanced system provided the two sections of the alarm wire system were symmetrical. However departure from this may be indicated where non-symmetrical signal wires exist and where the ground conditions underneath the signal wire system are different on the two sections. Measurements as to the change in capacitance with weather conditions and from day to night on the two sections of the signal wire system in general enable a more balanced system to result than the empirical method described above.

The inductance of the variable oscillator coil is then adjusted so that the audio signal fed from the selective network is approximately in the center of one of the steep sides of the resonance curve. This is indicated practically by the meter. This adjustment should be made with the compensating condenser plates about midway in mesh which allows for the maximum compensation in either direction. The bias on the various diodes is then adjusted so that the correction motors associated with the variable condenser will retain a suitable operating point on the resonance curve. The biases on the alarm relays are adjusted so that they operate at suitable points. The sensitivity of the system is then checked. If this sensitivity is too great, minor changes in sensitivity can be accomplished by adjusting the bias on the two alarm relays so that they are farther apart on the resonance curve. However if these minor adjustments do not give the desired sensitivity, the sensitivity can be further reduced by additional fixed condensers across the two oscillator circuits. A second operating point is obtained by adjusting the inductance of the variable oscillator coil and the same procedure as given above is followed. The inductance of the oscillator coil which I employ enables either the second and third, the third and fourth, the fourth and fifth harmonics to be employed. Naturally the higher the harmonics employed, the greater the sensitivity so that instead of changing the fixed condensers across the oscillator coils it may be possible if the sensitivity is too great for a given installation to vary the inductance sufficiently so that a lower set of harmonics are employed. The sensitivity may also be changed in a minor degree by relay adjustments on the alarm circuits.

In practice it has been found that condensers 28' and 29' (see Figure 4) in series with the alarm 60 wire system help the stability of the system under various weather conditions.

It should be noted particularly that the frequencies of both oscillators and therefore their harmonics will vary and that no attempt is made to keep any of these frequencies of either oscillator constant. In fact it is sufficient for maintaining balance that the difference between the harmonics, i. e., the beat frequency of the oscillators remain constant.

Having now described my invention I claim:

1. An electrical protective system for guarding against the approach of objects or persons comprising dual capacitance to ground elements extending about an area to be protected, means in-

cluding two separate oscillatory circuits operatively connected, each to one of said elements, said circuits with capacitance elements having each different oscillatory frequencies, means, actuated by the approach of an object or person to one of said capacitance elements to change differentially the frequencies of said oscillatory circuits, selective electrical circuit means operatively connected to said oscillatory circuits and selectively tuned to a beat frequency corresponding to the difference between different harmonic frequencies of said oscillators and means operatively connected to said selective electrical circuit for indicating by a change from a chosen beat frequency, the approach of an object or person.

2. A capacitance operated signal device comprising two signal wire systems having oscillatory circuits of different frequencies, a signal responsive means, non-responsive to a selected differential frequency of the combined different frequencies, but responsive to operation by other frequencies, means automatically providing adjustment of at least one of said oscillatory circuits of the different frequencies when slow differential capacitance changes take place per unit length on both said signal wire systems to maintain constant, said selected difference frequency, and means for operating said signal responsive means when relatively rapid capacitance changes alter materially said difference frequency from the selected value.

3. A capacitance operated device comprising two separate electrical oscillatory circuits having different oscillatory frequencies including signal wire systems connected, one to each of said oscillatory circuits and adapted to cause a differential change in the oscillatory frequencies by the approach of an object or person to one of said signal wire systems, a selective audio frequency amplifying network having a resonance characteristic curve with a point near the peak corresponding to a beat frequency between different harmonic frequencies of said oscillators in normal operation, means operative upon the variation of said beat frequency from its normal position for operating an alarm indicator indicating the presence of an object or person at said signal wire.

4. A capacitance operated device comprising two separate electrical oscillatory circuits having different oscillatory frequencies including signal wire systems connected, one to each of said oscillatory circuits and adapted to cause a differential change in the oscillatory frequencies by the approach of an object or person to one of said signal wire systems, a selective audio frequency amplifying network having a resonance characteristic curve with a point midway on the slope thereof corresponding to a beat frequency between different harmonic frequencies of said oscillators in normal operation, means operative upon the variation of said beat frequency from its normal position for operating an alarm indicator indicating the presence of an object or person at said signal wire, and means operative upon variations in the normal beat frequency less than the variation for causing the operation of the alarm to correct one of said oscillatory frequencies to return the beat frequency at a slow rate to its normal operating position.

5. An alarm system comprising dual capacitance to ground elements arranged to be proportionally affected by weather changes, compensating means operatively connected to said elements for maintaining a differential balance be-

11

tween said elements during said weather changes and electro-responsive means including an alarm means connected to said elements for producing an alarm when said differential balance has been upset by changes of a character different from said weather changes.

6. An alarm system comprising two independent electrical conducting wires extending over an area, the approach to which is to be guarded, means for electrically energizing said wires providing dual capacitance to ground elements, arranged and dimensioned to be substantially proportionally affected by normal weather changes, electro-responsive means, including alarm means, operatively connected to said conducting wires having electrical characteristics maintaining said alarm means unoperated during normal weather changes substantially proportionally affecting the capacitance to ground of said wires and operating said alarm means when the capacitance to ground of said wires are non-proportionately affected as by the approach of a foreign object to said wires.

7. An alarm system comprising means providing independent electric fields extending over an area the approach to which is to be guarded, said means adapted to have the capacitance to ground of each field substantially proportionally affected by normally expected climatic changes, signal means, means connected between the means providing the independent electric fields and said signal means for operating said signal means only under changes substantially non-proportionally affecting the capacitance to ground of each field.

8. An alarm system comprising two independent electrical conducting wire systems extending over an area, the approach to which is to be guarded, a pair of electric circuits each operatively connected to one of said conducting wire systems and each having impedance elements of different magnitudes apportioned for an electrical balance between each conducting wire system and its operatively connected electric circuit when each

12

conducting wire system is affected by the same climatic changes, and signal means operatively connected to said pair of electric circuits for operation thereby by an unbalance, when the conducting wire systems are affected by the approach of an object to the area to be guarded.

9. In a signal system, a double antenna system comprising two separate conductors of substantially equal electrical capacity to ground and extending in different directions from a common point, two oscillators respectively impressing on said conductors oscillating currents of predetermined frequencies, a converter tube having grids connected respectively with the output circuits of said oscillators whereby the output circuit of said converter tube has a beat frequency determined by said predetermined frequencies, an amplifier circuit, means feeding the output of said converter tube to said amplifier circuit, and a signal device operable by said amplifier circuit.

10. The combination of the preceding claim including filter means connected in circuit between said amplifier circuit and said signal device for selecting the frequency which will operate said signal device.
